UNITED STATES PATENT OFFICE.

ALFRED O. GIRARD, OF CHICAGO, ILLINOIS, ASSIGNOR, BY DIRECT AND MESNE ASSIGNMENTS, OF ONE-THIRD TO B. B. LIPSNER, ONE-THIRD TO PAUL SPORER, AND ONE-THIRD TO MILTON A. DREYFUS, ALL OF CHICAGO, ILLINOIS.

DISHWASHER NOZZLE.

Application filed April 24, 1922. Serial No. 556,190.

To all whom it may concern:

Be it known that I, ALFRED O. GIRARD, a citizen of the United States, residing at Chicago, in the county of Cook and State 5 of Illinois, have invented a certain new and useful Improvement in Dishwasher Nozzles, of which the following is a specification.

This invention is a novel form of dish 10 washer, more specifically a nozzle for delivering water, soapy or clear, at the will of the operator onto dishes with sufficient force so that it is unnecessary to otherwise wash them.

15 The object of the invention is to provide a mechanism which can be applied to the hot water faucet of a kitchen sink, or elsewhere as the facilities of the user may dictate, and which, when so applied, can be 20 conveniently used without any other mechanical apparatus for readily washing dishes or other articles which have to be cleaned by the use of hot water and soap.

The invention consists of a device for 25 attaining the foregoing objects, which can be easily and cheaply made, which is efficient and satisfactory in use, which is not readily liable to get out of order. More particularly, the invention consists in many 30 features and details of construction which will be hereafter more fully set forth in the specification and claims.

Referring to the drawings in which like numerals designate the same parts throughout the several views:

Figure 1 is a side view of mechanism illustrating this invention in its preferred form.

Figure 2 is a sectional detail view through the device of Figure 1.

40 Figure 3 is a sectional detail view on the line 3—3 of Figure 2.

Figure 4 is an end view of the nozzle case taken, as indicated by the arrows 4—4, of Figure 2.

45 Figure 5 is a view in the opposite direction, as indicated by the arrows 5—5, and at the same point as Figure 4, showing the interior of the permanent fixture to which the nozzle is attached.

50 Figures 6, 7 and 8 are sectional plan views through the three-way valve at the lines indicated by the corresponding arrows of Figure 2.

The device of this invention may be sup-

plied from any suitable source with washing liquid—presumably hot water—and water will accordingly be referred to as the washing agent without meaning thereby to limit the scope of the use of the invention. The source of such hot water is symbolized 55 in the drawing by a flexible tube 10, enclosed at its end by handle 12 and secured at 14 to the externally grooved lug 16 on a bracket member 18, to whose interior water is delivered through the passage 20 in member 16. Journaled in bracket 18 is a three-way valve 22, manipulatable from outside the device by any conventional form of handle 24, and adapted to conventionally switch water delivered from pipe 10 through passage 20 to either one of two separated discharge ports 24^a and 26 in the bracket, each opening inside of a cylindrical flange member 28 provided with securing devices such, for instance, as bayonet joints 30 for attaching the nozzle case 32 to this flange 28 and thereby to the bracket 18.

55 Nozzle case 32 is hollow and made with two interior water passages 34 and 36 leading to different selected groups of small 60 discharge spray ports 38 and 40.

As shown in the drawing, the passage 36 is larger than passage 34 and its intake or righthand end, as viewed in Figure 2, is made sufficiently large so that a suitable 65 cup—in the particular case here illustrated—a cylindrical one 42 may be inserted within the passage 36 in engagement with suitable supporting lugs 44 in such a position that water delivered from passage 26 70 may enter the free open end 46 of the cup 42 and engage flakes or lumps of soap 48 contained within the cup 42, principally at its opposite or closed end 50, and thence 75 pass out of the case through a multiplicity 90 of small side perforations 52, leading into the passage 36 proper, and thence to the discharge spray ports 40. A tube 53 is 80 preferably inserted in port 26 and carried into case 42 beyond ports 52 so as to insure 100 the water's making active contact with the soap 48.

In the operation of the device, when assembled as shown in Figures 1 and 2, the operator first grasps the handle 12 and then 105 moves the handle 24 of valve 22 to direct the hot water from pipe 10 into the soap 48 and thence to the spray ports 40. In so

passing, the water takes up considerable soap and is delivered from the ports 40 as soapy water which, on striking the dishes suitably disposed in a rack or the like, thoroughly cleanses them. As soon as the dishes are thus cleansed, the operator turns handle 24 to switch the water from passage 36 to passage 34, thereby directing clean hot water through spray ports 38 onto the dishes to thoroughly rinse them. The heat in the water should be sufficient so that when the dishes are rinsed, they can be allowed to dry without wiping with a towel.

The operation of filling the device with soap is practically obvious: The operator merely rotates case 32 to release the bayonet joint connections 30, whereupon the soap receptacle 42 can be refilled, either with or without removing it from its position 20 against the lugs 44. When the soap receptacle has been refilled, the nozzle 32 and attached parts are replaced inside of flange 28 and conventionally rotated to tighten bayonet joints 30.

Figures 4 and 5 show the end of passage 32 as of segmental cross-section 34^a and the end of passage 24, correspondingly as 24^a. These are used merely to insure a free passage of water regardless of wear which may 30 take place in the bayonet joints 30 to change the angular position of the nozzle case 32 with reference to the bracket 18 when the parts are finally locked together.

What I claim is:

1. A dish washer nozzle of the class described having two groups of perforations for spraying the dishes and comprising two independent passages terminating in the groups of perforations, one of said passages being formed to hold a quantity of soap to be dissolved, a third passage for supplying water under pressure to the nozzle, the passages being so related in size as to insure the projection of sprays from the respective groups of perforations, and means for selectively directing water from said third passage through said independent passages to the groups of perforations.

2. A dish washer nozzle of the class described having two groups of perforations for spraying the dishes and comprising independent passages terminating in the groups of perforations, a perforate wall in one of said passages for retaining a quantity of soap to be dissolved, a third passage for supplying water under pressure to the nozzle, the independent passages and said third passage being so related in size as to insure the projection of sprays from the re-

spective groups of perforations, and means 60 for selectively directing water from the third passage through said independent passages to the groups of perforations.

3. A dish washer nozzle of the class described having two groups of perforations 65 for spraying the dishes and comprising two independent passages terminating in the groups of perforations, a removable perforate receptacle for soap in one of said passages, a third passage for supplying water 70 under pressure to the nozzle, the passages being so related in size as to insure the projection of sprays from the respective groups of perforations, and means for selectively directing water from the third passage 75 through said independent passages to the groups of perforations.

4. A dish washer nozzle of the class described having two groups of perforations for spraying the dishes and comprising two 80 independent passages terminating in the groups of perforations, a third passage for supplying water under pressure to the nozzle, the passages being so related in size as to insure the projection of sprays from the 85 respective groups of perforations, means for selectively directing water from the third passage through said independent passages to the groups of perforations, and a removable receptacle for soap in one of said independent passages so as to be engaged by water traversing the passage, said receptacle being cup-shaped and having an imperforate bottom wall and a perforate side wall, the open end of the cup being disposed 90 to receive water directed to said independent passage.

5. A dish washer nozzle of the class described and embodying a plurality of members detachably secured to each other, one 100 of said members having two groups of perforations for spraying the dishes and comprising two independent passages terminating in the groups of perforations, one of said independent passages being enlarged 105 to hold a quantity of soap to be dissolved, the other of said members comprising a third passage for supplying water under pressure to the nozzle, the third passage and the independent passages being so related in size 110 as to insure the projection of sprays from the respective groups of perforations, and means for selectively directing water from the third passage through said independent passages to the groups of perforations. 115

In witness whereof, I have hereunto subscribed my name.

ALFRED O. GIRARD.
